UNITED STATES PATENT OFFICE

FRED A. TARRIER, OF COLUMBUS, OHIO

FENCE CONSTRUCTION

Application filed February 21, 1928. Serial No. 256,035.

This invention relates to an improved fabricated fence, and has for its primary object the provision of a fence which may be constructed to include standardized sections 5 each of which being so formed as to possess maximum mechanical strength and durability and which may be formed from standard materials at low manufacturing expense.

Another object of the invention resides in 10 a fabricated fence section of the above character wherein the various parts of the fence section are united through welding for the purpose of producing an extremely rigid or inflexible construction fully capable of 15 withstanding the stresses and strains of practical use.

A further object of the invention rests 20 in the provision of improved connecting means between the various adjacent sections 25 of the fence, by means of which said sections may be securely connected in various positions of alignment or angular relationship with respect to each other, the connecting means being of a standardized construction and adaptable throughout all positions 30 of angular relation between adjacent fence sections.

With these and other objects in view as 35 will appear as the description proceeds, the invention consists in the novel features of construction, combinations of elements and arrangements of parts hereinafter to be more fully described and pointed out in the appended claims.

35 In the accompanying drawings:

Figure 1 is a side elevation of a fence 40 formed in accordance with the present invention,

Figure 2 is an enlarged top plan view of 45 the fence, disclosing a pair of adjoining sections,

Figure 3 is a side elevation of a connector utilized in uniting the fence sections,

Figure 4 is a horizontal sectional view 50 showing the connecting members in positions to unite intersecting fence sections,

Figure 5 is a perspective view of one of the connectors,

Figure 6 is a horizontal sectional view

through a slightly modified form of connector,

Figure 7 is a side elevation of the connector disclosed in Figure 6,

Figure 8 is a perspective view of a portion 55 of the fence body.

Referring more particularly to the drawings the numeral 1 designates a section of a fabricated fence formed in accordance with the present invention. A plurality of 60 such sections are, of course, used in connection with a complete line of fencing, but since such sections are duplicates, a detail description of one section will suffice for all.

In the preferred embodiment of the invention each section is formed to include at its opposite ends a pair of transversely spaced vertically extending rods 2, to which are welded horizontally extending, transversely spaced upper and lower sets of longitudinally extending brace rods 3, the ends of the latter being welded as at 4 to the upright post rods 2. Between the brace rods 3 I provide angularly extending sets 70 of cross rods 5, which have their intersecting portions welded to each other and also welded to the rods 2 and 3 where the cross rods contact or engage with the rods 2 and 3. It will be seen that by using standard 75 metallic rods and by arranging and connecting the same in the manner illustrated and described, I am enabled to produce an extremely rigid and durable fence section at a comparatively low cost, of superior 80 strength and one fully capable of conforming to the needs and exigencies of fence construction. If desired the upper ends of the cross rods 5 may be terminated above the brace rods 3 and sharpened or pointed, as 85 disclosed, to discourage one from endeavoring to climb over the fence. The spacing between the cross rods 5 is proportioned so as to prevent a person of normal size from crawling between the openings in the fence.

To unite the various sections of the fence I have provided a connector disclosed particularly in Figures 2 to 5 inclusive. The connector consists of duplicate sections 6 of the type shown in Figure 5. Each section 100

includes a casting or forging 7 having one surface thereof recessed as indicated at 8 and provided with spaced vertical apertures 9. One end of the casting body 7 is provided 5 with spaced vertical grooves adapted to register with corresponding grooves provided in a cap piece 10, which grooves are adapted to receive the upright post rods 2. Fastening screws 11 pass through the cap pieces or 10 sections 10 and are threaded into openings formed in the casting bodies 7. By tightening the screws 11 it will be seen that the connectors will be frictionally and firmly secured in a removable manner to the post rods 15 2 at any desired position thereon. The complementary portions of the castings 7 are then united by means of bolts 12, which pass through one or the other of the sets of vertical apertures 9 or through both sets, as 20 the case may be.

This construction lends itself readily to the connecting of adjoining fence sections when such sections are in relative longitudinal alignment, as shown in Figure 2. In addition to this, however, the connection has the advantage of permitting of the ready assembling of the fence sections in relatively angular positions of association. An extreme condition has been shown in Figure 4 where- 25 30 in the connectors are employed for uniting intersecting fence sections, or sections arranged at an angle of ninety degrees with respect to each other. In this form of the invention the bolt 12 is passed through the openings 9 provided in the outer portions of the body 7 of said connectors, producing a very secure union without involving the necessity of employing special fastening means or fittings.

40 In Figures 6 and 7 a slightly modified form of coupling has been disclosed but wherein substantially the same principles are present. In this form of the invention the coupling consists of main body sections 45 13, provided with complementary planer surfaces 14, which are formed with registering apertures and adapted for the reception of a single fastening bolt 15. The body sections 13 are united to the upright posts 2 by means of removable clamping sections 50 16, the latter being held in place by threaded bolts 17.

The lower ends of the post rods 2 may be embedded in a connector foundation as indicated at 18, although in practicing the invention such a foundation may not be provided, since the posts are capable of being driven directly into the ground and are of sufficient length to retain the fence sections 60 in stabilized positions.

In view of the foregoing it will be seen that the present invention provides a simple and improved type of structural metal fence which may be readily adapted to 65 fencing requirements generally and has for

some of its outstanding advantages, over ordinary types of fence construction, greater mechanical strength, economy in manufacturing, assembling and erection costs and permits of the use of standardized materials. 70

While I have described what I consider to be the preferred forms of the present invention, never-the-less it will be understood that various changes may be made in 75 the construction of the fence from time to time from the specific forms above described and disclosed without departing from the spirit of the invention and the scope thereof as such invention has been 80 defined in the following claims.

What is claimed is:

1. A fabricated fence comprising a pair of transversely spaced upstanding post rods at each end thereof, upper and lower sets 85 of longitudinally extending horizontally disposed and transversely spaced brace rods having the ends thereof connected with said post rods, and a plurality of angularly extending relatively intersecting cross rods 90 arranged between the post and brace rods and welded to said post and brace rods at points where the latter are in engagement with the cross rods.

2. A fabricated fence section comprising 95 a pair of transversely spaced vertically extending post rods arranged at the opposite ends of said section, upper and lower pairs of horizontally disposed transversely spaced and longitudinally extending brace rods 100 having the ends thereof welded to said post rods, and a plurality of angularly extending relatively intersecting cross rods arranged between said post and brace rods and welded thereto, relatively parallel cross 105 rods being arranged in the same vertical plane.

In testimony whereof I affix my signature.

FRED A. TARRIER.
